UNITED STATES PATENT OFFICE.

JOHN B. PIERCE AND JOSEPH BOND, OF BUFFALO, NEW YORK.

STEAM-RADIATOR.

SPECIFICATION forming part of Letters Patent No. 316,055, dated April 21, 1885.

Application filed December 28, 1883. (No model.)

To all whom it may concern:

Be it known that we, JOHN B. PIERCE and JOSEPH BOND, citizens of the United States, residing in Buffalo, in the county of Erie and State of New York, have invented certain new and useful Improvements in Steam-Radiators, of which the following is a specification.

The object of this invention is to produce a simple, cheap, and durable steam-radiator for heating buildings, &c., all of which will be fully and clearly hereinafter shown and explained by reference to the accompanying drawings, in which—

Figure 1 is a side elevation of a single section of the radiator. Fig. 2 represents a side elevation of a series of sections put together, showing the radiator complete. Fig. 3 is a vertical section through a series of radiator-sections in line $x-x$, Fig. 1. Fig. 4 is a top view of a radiator-section. Fig. 5 is an enlarged cross-section through one side of a radiator-section in line $z-z$, Fig. 1; and Fig. 6 is a vertical central section through the lower portion of a radiator-section.

The sides of the radiator-section $a-a'$ are in the form of a rhombus in cross-section, having the flat sides a^6 . (See Fig. 5.) Each side a a' is a thin shell of cast-iron and of an even thickness throughout and perfectly plain, so that all the benefit possible from the steam is obtained, as all parts of the shell are of an even thickness, having no thick or uneven portions to obstruct the passage of the heat. Besides, the form of the sections in cross-section exposes a great deal of surface in a given space and permits a freer circulation of air than the forms usually used for such purposes. Each section is provided near the top with a small projection, a^2-a^3 . The one marked a^2 is provided with a pointed end, a^4 , and a^3 has a depression, a^5 , of corresponding form, to receive the projecting portion of a^2 .

b is the binding-rod for the purpose of holding the top of the section together. The lower portion of the sections are held together by the short tubes or plain nipples b' , the tubes being put in place and the whole forced together by a hydraulic press or other well-known means. Of course the sections may be

secured together by screw-threaded nipples 50 in the usual way; but they would not answer the purpose so well and could not be so cheaply constructed. The parts b^2 between the sections being cylindrical, there is no base upon which dust can gather in any great quantities. 55 The openings b^3 b^4 may be placed (as b^3 is) to the left-hand side of the section, and the opening b^4 on the opposite side of the section may be placed to the right, as shown by the dotted lines. (See Fig. 1.) In this way the steam 60 would run diagonally from one section to the other as it circulates through them. A diaphragm, b^5 , may be placed between the openings b^3 b^4 , if required, (see Fig. 6;) or said openings may be set directly opposite each 65 other, if desired.

The object in making the nipples straight instead of conical is, that, when the holes and nipples are made perfectly straight and the nipples slightly larger, and the whole forced 70 together by a powerful press, a very strong connection is made, being almost as strong as if the radiator sections were formed in one solid piece, and consequently no binding-rod is required to hold them together. The sec- 75 tions, being formed in one piece, are stronger, more durable, and not liable to leak, and can be more cheaply made, and being in the form of a rhombus, or substantially so, form, when a series are put together, as above mentioned, 80 a more compact radiator and expose a larger heating-surface in proportion to the space occupied. It also leaves a greater space between the sections for a more free circulation of air than it would if made in the ordinary way 85 with a base, as a base obstructs the circulation of the air.

It will be noticed that in our construction the usual base is dispensed with, so that there is nothing to obstruct the free circulation of 90 air upward from the bottom between the sections.

We are aware that the sections of a radiator have been put together with conical or taper nipples, the sections being provided 95 with a corresponding taper-hole to receive them. It will be readily seen that a taper-nipple will instantly separate from the sec-

tion when once it becomes loose. We therefore do not claim such construction; but

What we do claim as our invention is—

A radiator consisting of a series of radiator-sections having plain or smooth straight openings b^3 b^4 , in combination with a series of plain short tubes or nipples of equal diameter throughout, the whole combined and

put together, substantially as and for the purposes described.

JOHN B. PIERCE,
JOSEPH BOND.
